UNITED STATES PATENT OFFICE.

OTTO HEINZELMAN, OF BELLEVILLE, ILLINOIS, ASSIGNOR OF ONE-THIRD
TO J. E. THOMAS, OF SAME PLACE.

SIDE-BAR VEHICLE.

SPECIFICATION forming part of Letters Patent No. 377,382, dated February 7, 1888.

Application filed February 24, 1887. Serial No. 228,750. (No model.)

To all whom it may concern:

Be it known that I, OTTO HEINZELMAN, a citizen of the United States, residing at Belleville, in the county of St. Clair and State of Illinois, have invented certain new and useful Improvements in Side-Bar Vehicles; and I do hereby declare the following to be a full, clear, and exact description of the invention, such as will enable others skilled in the art to which it appertains to make and use the same.

My invention relates to improvements in side-bar vehicles, and has for its objects to form the side bars and bolster in one piece with a bent or curved portion forming a bearing and brace for the upper leaf of the fifth-wheel; second, to improve the construction of the fifth-wheel; and, further, to afford simple and efficient means for securing the side bars to the rear axle.

To the accomplishment of the foregoing objects the invention consists in the construction and the combination of parts hereinafter particularly described, and then sought to be specifically defined by the claims, reference being had to the accompanying drawings, forming a part hereof, and in which—

Figure 1 is a perspective of the invention attached to the axles of a vehicle, a portion of the bolster plate or bar being broken away. Fig. 2 is a longitudinal section on the line *xx* of Fig. 1. Fig. 3 is a plan of the top and bottom leaves of the fifth-wheel.

The side bars (designated by the letter A) are made from metal or other suitable material of any desired thickness, and at their forward ends are connected together by a plate, B, preferably made integral with said bars, being a continuation thereof and constituting the bolster-plate or head-block of the vehicle. This bolster-plate, at the proper point between the side bars, is formed with a forwardly-extending bend or curve, C, which will form a bearing and brace for the upper leaf of the fifth-wheel and practically form a part thereof.

The upper leaf, D, of the fifth-wheel is given substantially the same bend or curve as the bolster-plate, and extends forward of a plate or bar, E, which is formed with an extension or ear, F, for the passage of a king-bolt. The upper leaf is secured by suitable means—say by rivets *a*—to the bolster-plate B. The lower

leaf, D', is formed similarly to the upper leaf, with a bar or plate, E', and extension or ear F', and is secured by suitable means—for instance, by bolts G—to the front axle, H. The two leaves are secured together, so that one will turn upon the other by means of a king-bolt, I, passed through the ears of the two leaves. For the purpose of more securely guarding against one leaf being separated from the other, a clip, J, is made to embrace the extension of the bolster-plate and the lower leaf, and is secured to one of them by means of a rivet or otherwise.

If the continuation of the bars A be divided at the curve, as it may be for convenience in making, the clip J will be secured by two rivets, one on each side of the dividing-line, as shown in Fig. 1. The rear ends of the side bars rest upon the rear axle, H', and are secured thereto in some suitable way, preferably by the following means: A block, K, extends from the under side of each side bar, and is preferably made separate therefrom and secured thereto by means of rivets *b*. Each block has formed in its lower face a socket or cavity, L, designed to fit down over the axle, thus forming shoulders which prevent the axle from moving under the side bars. Before the blocks are riveted to the side bars bolts M are passed through the blocks, so as to lie on opposite sides of the axle, and after a clip-plate, N, is passed over the lower ends of the bolts, so as to lie against the under side of the axle, nuts O are screwed up on the bolts, so as to clamp the axle between the blocks, bolts, and clip-plates, and thus securely bind the parts together.

Under the construction and arrangement of parts described, the two axles are connected together by the side bars, which latter are extended to form the bolster-plate, and the plate extended to form a bearing and brace for the fifth-wheel and a part of the latter, the whole forming a strong, simple, and efficient side bar, bolster-plate, and fifth-wheel inexpensive to manufacture and quickly and easily applied. I have described what I consider the best details of construction for the ends in view; but it is apparent that changes can be made that would be embraced within my invention.

Having described my invention and set forth

its merits, what I claim, and desire to secure by Letters Patent, is—

1. The side bars connected together at their forward ends by a bar made integral therewith and forming a bolster-plate, and having a bend therein, substantially as shown, forming part of the fifth-wheel, substantially as described.
2. The combination of the side bars connected together at their forward ends by a cross-bar, a plate secured to said cross-bar and having an extension on one side to form one leaf of the fifth-wheel, and an ear on the opposite side for the passage of a king-bolt, and a second plate having an extension and ear corresponding to those of the first plate to form a second leaf of the fifth-wheel, substantially as described.
3. The combination of the fifth-wheel formed of the two plates having the extensions constituting the leaves and the ears for the pas-

sage of the king-bolt, the side bars connected together at their forward ends by a cross-bar which is bent or curved to form a bearing or brace for the fifth-wheel, and a clip embracing the lower leaf of the fifth-wheel and the cross-bar of the side bars, substantially as described.

4. The combination of the side bars, the rear axle, the blocks depending from the side bars and formed with sockets to embrace the axle, bolts passed through said block on opposite sides of the axle, with their heads lying below the side bar, substantially as shown, and clips and nuts for clamping said parts together, substantially as described.

In testimony whereof I affix my signature in presence of two witnesses.

OTTO HEINZELMAN.
